UNITED STATES PATENT OFFICE.

EDWARD R. STILES, OF DECATUR, ILLINOIS.

RAILWAY-RAIL TIE.

SPECIFICATION forming part of Letters Patent No. 605,356, dated June 7, 1898.

Application filed August 20, 1897. Serial No. 643,932. (No model.)

To all whom it may concern:

Be it known that I, EDWARD R. STILES, of Decatur, in the county of Macon and State of Illinois, have invented a new and Improved 5 Railway-Rail Tie, of which the following is a full, clear, and exact description.

The object of the invention is to provide a railway-rail tie which may be made principally of metal and which will be simple, durable, and economic in its construction.

Another object of the invention is to provide a means whereby the rail will not creep and to provide a firm bed for the rail and one which will be calculated to deaden the sound and 15 also to provide a means whereby the blocks upon which the rails rest will be held against end movement.

The invention consists in the novel construction and combination of the several 20 parts, as will be hereinafter fully set forth, and pointed out in the claims.

Reference is to be had to the accompanying drawings, forming a part of this specification, in which similar characters of reference indicate corresponding parts in all the figures.

Figure 1 is a plan view of the improved tie. Fig. 2 is a side elevation of the same. Fig. 3 is an end view. Fig. 4 is a partial plan view of a modified form of the tie. Fig. 5 is a partial side elevation of the modified form of the tie, and Fig. 6 is an end view of the same.

The body of the tie consists of a channel-bar A of suitable length and constructed of metal. At the central portion of the channel-bar, in the bottom thereof, the metal is struck downward to form lugs 10, which will enter the ground upon which the bar is placed and will serve to hold the said bar in position. The flanges of the channel-bar are reinforced 35 by fillets 10^a. Blocks B, preferably of wood, although they may be made of metal, are placed in the channel-bar engaging with the bottom thereof, the blocks being of such width as to fit neatly between the flanges of the bar. Two blocks are employed, one near 40 each end of the channel-bar, and when the blocks are made of wood, as shown in Figs. 1, 2, and 3, the bottom portion is cut away to form an inclined surface, the inclination being from the back downward. With the exception of the inclined surfaces 12 the outer 45 ends of the blocks are preferably straight,

and their inner ends are inclined from top to bottom.

In connection with each wooden block a 55 shoe 13 is employed, the shoes being made of metal. Each shoe consists of a member a, which has an inclination corresponding to the surface 12 of the block, and a horizontal member a', the two members being strengthened 60 by ribs a². (Shown best in Figs. 1 and 2.) The horizontal members of the shoes are bolted or otherwise secured to the channel-bar and serve to prevent the blocks B from being forced outward to the end portions of 65 the channel-bar. The blocks, however, are secured directly to the channel-bar through the medium of bolts 14, which are passed diagonally through their front and rear end portions and through the bottom of the channel-bar, the lower ends of the bolts which extend beyond the bottom of the channel-bar being provided with suitable nuts 15, the lower ends of the bolts 14 and the nuts 15 serving in the 70 same capacity as the lugs 10—namely, to assist in holding the tie in position.

As additional fastening devices for the blocks B screws or plugs 16 or their equivalents are passed through the flanges of the channel-bar into the side portions of the 80 blocks. The rails 17 are held upon the upper surface of the blocks B by means of clamps 18 of any approved type, the clamps being fastened to the blocks by means of bolts 19, which extend through the blocks and through 85 the bottom of the channel-bar, serving also to secure the blocks to the bar. The rails cross the blocks near their inner ends to equalize the bearing of the blocks upon the channel-bar. The depth of the blocks is usually 90 five to seven inches.

In Figs. 4, 5, and 6 I have illustrated the application of metal blocks B to the channel-bar. These metal blocks consist each of two upright pedestals 20, their end portions being 95 preferably inclined downwardly in opposite directions, each pedestal being preferably provided with an outwardly-extending horizontal flange 21 at the top and a similar flange 22 at the bottom. The pedestals are spaced 100 apart by an interposed wooden block 20^a, secured to the pedestal by bolts 20^b or like devices, as shown in Fig. 6. Clamps 23 are secured upon the upper flanges 21 of the pedes-

tals of the blocks and engage with the flanges of the rails 24, which rest upon the said top flanges of the pedestal nearer the inner than the outer end portions of the blocks.

5 The outer clamp 23, attached to the metal block, is carried upward upon a curved line to engage with the head of the rail and serves as a brace. The fillets 10^a are very important, as their introduction increases the thickness 10 of the tie more than double that of any other part and adds to the life of the channel-bar, as the corners where the fillets are applied are the only parts of the tie subjected to material wear. The rails can be fastened upon 15 wooden blocks by spiking or bolting, as desired. By placing the rail-seats nearer the inner end of the blocks, in addition to equalizing the bearing, room is provided for rail-braces when desired.

20 Having thus described my invention, I claim as new and desire to secure by Letters Patent—

1. The combination with a channel-bar, of 25 blocks fitting in said bar, each block having the lower portion of its outer end inclined upwardly and outwardly and its inner end inclined from top to bottom, shoes secured in the channel-bar and having an inclined face resting against the outer inclined portion of 30 the block, and bolts extending through the blocks and bottom of the channel-bar, substantially as described.

2. The combination, with a channel-bar provided with fillets upon its inner face at its

flanges, of blocks fitted to the said bar, each 35 block having the lower portion of its outer end inclined, shoes secured to the said bar and fitting between the flanges thereof, the said shoes comprising a horizontal member and an inclined member engaging with the 40 inclined portions at the outer ends of the blocks, clamps secured upon the upper surfaces of the blocks, and fastening devices auxiliary to the said shoes, arranged to hold the blocks firmly in engagement with the said 45 channel-bar, as and for the purpose specified.

3. The combination, with a channel-bar having fillets formed upon its inner face at its flanges, portions of the bottom of the bar being struck downward forming anchors for 50 the bars, of blocks fitted in the said channel-bar, shoes secured to the channel-bar between its flanges and having inclined faces engaging with the corresponding faces at the lower portion of the outer ends of the blocks, 55 bolts passed through the blocks and through and beyond the bottom of the channel-bar, serving as auxiliary anchors for the bar, clamps adapted for engagement with the rails, secured upon the upper surface of the blocks 60 nearer their inner than their outer ends, and bolts passed through the said clamps, through the blocks and through the bottom of the channel-bar, for the purpose set forth.

EDWARD R. STILES.
